UNITED STATES PATENT OFFICE.

NORMAN B. JONES, OF MURPHYSBOROUGH, ILLINOIS.

LEATHER-CUTTER.

SPECIFICATION forming part of Letters Patent No. 358,779, dated March 1, 1887.

Application filed December 4, 1886. Serial No. 220,711. (No model.)

To all whom it may concern:

Be it known that I, NORMAN B. JONES, a citizen of the United States, residing at Murphysborough, in the county of Jackson, State of Illinois, have invented certain new and useful Improvements in Leather-Cutters, of which the following is a specification, reference being had therein to the accompanying drawings.

This invention relates to devices for cutting leather, and more particularly to that class thereof for cutting whangs, shoe-strings, straps, and strips; and the object of the invention is to provide a cheap and simple device of the above character which is easy of manipulation and effective in operation.

Other objects and advantages of the invention will appear in the following description, and the novel features thereof will be particularly pointed out in the claims.

Referring to the drawings, Figure 1 is a plan view of my invention. Fig. 2 is a perspective of the table detached. Fig. 3 is a side elevation of the handle of that side thereof opposite the table, and Fig. 4 is a side elevation opposite that shown in Fig. 4. Fig. 5 is a detail in perspective of the traveler.

Like letters of reference indicate like parts in all the figures of the drawings.

A represents the handle, which is formed with the socket or projecting portion A', and which is provided with the transverse recesses A² A³ (see Fig. 4) and the vertical recess A⁴. (See Fig. 3.)

B represents the table, which is of substantially disk shape, and is provided with the cut-away or recessed portion, B', and the forwardly-projecting arms B², which are adapted to enter into the recesses A² of the socket. Formed on the surface of the table is a longitudinal groove or way, B³, and adapted to ride therein is a traveler, B⁴, (see Fig. 5,) at one end of which is an upwardly-projecting spur, B⁵.

Within the recess A⁴ is a block, A⁶, which is provided with an overlapping or projecting portion, A⁶, under which the leather passes when being revolved upon the table, and is slotted, as at A⁷, for the reception of a set-screw, A⁸, whereby said guiding-block is vertically adjustable.

A block, A⁹, carrying a knife, A¹⁰, is adapted to enter the transverse slot A³ of the socket, said block being held in position by means of a

set-screw, A¹¹, inserted longitudinally through the forward end of the socket and bearing on said block, whereby said knife and block are adjustable to and from the table. The knife A¹⁰ is provided with two cutting-edges, and is removably mounted in a transverse slot in the block, it being held in a fixed position therein by means of a set-screw, A¹², passing longitudinally through said block. By reason of the knife being removable from the block and provided with two cutting-edges it may be reversed, bringing either cutting-edge into operation.

The operation of my invention is readily apparent from the above description, and is as follows: If it be desired to cut a strip or whang from a piece of leather, X, the spur B⁵ is inserted at the center thereof, it being understood that the device is held in one hand and the cut is then started by drawing the leather between the knife and guard or guiding block A⁶. By taking hold of the portion or strip thus started and drawing steadily upon the same a strip of leather of desired width may be drawn or cut, the length of which is only governed by the size of the piece from which the strip is being cut, or it may be severed into suitable lengths by drawing the strip transversely against the opposite cutting-edge of the knife. As the leather is cut the piece revolves upon the spur B⁵ of the traveler B⁴, which automatically moves along the groove B³ toward the knife. B⁴ is in reality a centering-traveler, in that it automatically moves toward the knife A¹⁰ in relation to the amount of leather removed by said knife, so as to keep the center of rotation of the leather at a proper distance from the knife to insure a uniformity in the width of the whangs. While it is possible, by removing the centering-traveler from the table, to cut straight pieces or straps, it is preferable to remove the table also, as the material—for example, a side of leather—from which a strap is to be cut is always at the side of the knife at which the table is located, and therefore the instrument can be used with greater ease and accuracy if the table is removed. I therefore have shown one form of construction which permits the removal of the table, and which, by reason of the tendency of the movement of the material X upon the table to draw the

table toward the knife, is a sufficient means of connecting the table to the latter. Still, as before stated, I deem the removable connection of the table to the handle as a broad and important feature of my invention. By adjusting the knife-carrying block A⁹ toward or from the guide-block A⁵ the width of the strip may be varied as desired.

By reason of the guide-block A⁵ being adjustable vertically different thicknesses of leather—or, in fact, two or more layers—may be cut at the same operation, the block being adjustable to such a position as to allow them to pass freely under the overlapping portion A⁶ of the same, thus presenting the leather squarely to the knife and rendering the strip being cut uniform, which otherwise would not be the case, as the leather has a tendency to curl when brought into contact with the knife. Upon the handle is formed a fixed guide, A¹³, which coacts with the adjustable guide to produce a strip of uniform width.

If desired, the table B may be removed and the handle and knife used to cut straps, halters, &c., from straight pieces of leather. For this purpose the socket portion of the handle is adapted for the removable connection therewith of the table, as hereinbefore described; but I do not limit my invention to the exact form of table and knife connecting joint or joints shown and described as and for the purpose of the removable connection of these with each other. The table being of sheet metal, it is convenient to form thereon the arms B², which are in their nature and purpose similar to a tenon, while the recesses A² of the handle or socket are in their nature similar to a mortise. Therefore it is to be understood that I may substitute for this construction any well-known detachable connecting construction.

Having thus fully described my invention and its operation, what I claim is—

1. In a leather-cutter, the combination of a handle provided with a knife, of a table removably connected with the handle, and a 45 centering-traveler, substantially as specified.

2. In the leather-cutter herein described, the combination of a handle having a socket recessed to receive a knife-carrying block, with a table adapted to enter recesses formed in the 50 socket and provided with a leather-carrying traveler, all substantially as specified.

3. In a leather-cutter, the combination of a handle provided with an adjustable knife and guard and recesses, with a table adapted to 55 enter said recesses, substantially as specified.

4. The combination of the handle A, formed with the socket portion A' and recesses A² A³ A⁴, with the adjustable knife-carrying block A⁹, having the knife A¹⁰, the guiding-block A⁵, 60 slotted, as at A⁷, and having the set-screw A⁸, with the table B, having the guide or way B³, recessed, as at B', and provided with the projections B², adapted to enter recesses in the socket, substantially as shown and described. 65

5. The combination of the table B, having the recess B' and projections B², and provided with the longitudinal groove B³, and the traveler B⁴, mounted in said groove and having the spur B⁵, of the handle A, having the recessed socket A', adapted to receive said table, substantially as specified. 70

In testimony whereof I affix my signature in presence of two witnesses.

NORMAN B. JONES.
